UNITED STATES PATENT OFFICE.

SYDNEY ALLEN CURRIN, OF BRISTOL, ENGLAND.

DUST-CAP FOR PNEUMATIC-TIRE VALVES.

1,034,209.

Specification of Letters Patent. Patented July 30, 1912.

Application filed April 14, 1911. Serial No. 621,144.

To all whom it may concern:

Be it known that I, SYDNEY ALLEN CURRIN, a subject of the King of England, residing at Bristol, England, have invented 5 certain new and useful Improvements in Dust-Caps for Pneumatic-Tire Valves, of which the following is a specification.

This invention is for improvements in or relating to dust-caps for pneumatic-tire 10 valves and has for its object to provide a cap that can be more readily handled than those at present in use and entirely covers or incloses and protects the whole of the valve parts.

15 An important feature of the invention consists in the combination of a socket or tubular base to be permanently fixed in the wheel-rim and through which the valve can freely pass, and a cover formed of thin spun 20 material which can be sprung instead of screwed on to the socket or tubular base and which entirely incloses the whole of the valve parts.

In the accompanying drawings which 25 illustrate one method of carrying out this invention—Figure 1 shows the detachable cover of the cap, part being broken away for clearness; Fig. 2 shows the socket portion, and Fig. 3 is a plan of the socket.

30 Like letters indicate like parts throughout the drawings.

The base portion a is tubular and is conveniently spun from thin metal, one end having formed on it a screwthread as at a' 35 for screwing into the felly of the wheel. At the base of the screw-thread is a shouldered portion a^2 and at the other end of the socket is an annular recess a^3 . This end of the socket moreover is split at a^4 into four parts. 40 The cover b may also be formed from spun material, and is closed at one end and open at the other. At a point intermediate of its ends, the cap b is formed with an annular groove or dépression to provide a locking 45 element complementary with the locking element a^5 of the tubular member a . And the location of said groove b' leaves a projecting portion b^2 whose marginal edge b^3 engages with the annular shoulder a^2 when

the cap is in applied position. The socket 50 or tubular base being sufficiently large to permit the valve to pass through it, need never be removed from the felly and the valve can be introduced or withdrawn even when the cover b is in place. The cover, as 55 will be seen, snaps on to the socket instead of screwing on to it, the split end of the socket readily yielding for this purpose although being sufficiently stiff to retain the cap in place when the inferior rib b^4 has 60 engaged the recess a^3 .

It is to be understood that slight changes in the form, proportion, and minor details of construction may be resorted to without sacrificing any of the advantages or departing from the spirit of the invention.

What I claim as my invention and desire to secure by Letters Patent is:—

A dust cap for pneumatic tire valves comprising a tubular member having a screw-threaded portion, a split portion providing resilient segmental sections, and an annular shoulder located intermediate of said screw-threaded and split portions; said screw-threaded portion adapted to have engagement with the wheel rim, and said split portion adapted to project therefrom and provided with an annular recess forming a securing element; and a cap having a closed and an open end, and constructed with an 70 intermediate annular recess providing an internal securing element complementary to the securing element of the tubular member, and leaving a projecting portion at the open end; said cap adapted to fit over the split 75 tubular portion and be held thereon through engagement of said securing elements, and the edge of said projecting portion of the cap adapted to engage with the annular collar of the tubular member, substantially 80 as described.

In testimony whereof I have signed my name to this specification in the presence of two subscribing witnesses.

SYDNEY ALLEN CURRIN.
